Patented Mar. 10, 1914.

UNITED STATES PATENT OFFICE.

WILLIAM A. WATKINS, OF RIVERSIDE, CALIFORNIA, ASSIGNOR OF ONE-HALF TO
SIDNEY A. RATLIFF, OF RIVERSIDE, CALIFORNIA.

AIR-SUPPLY MEANS FOR MOTORS.

1,089,998.

Specification of Letters Patent. Patented Mar. 10, 1914.

Application filed June 20, 1913. Serial No. 774,927.

To all whom it may concern:

Be it known that I, WILLIAM A. WATKINS, a citizen of the United States, residing at Riverside, in the county of Riverside and State of California, have invented new and useful Improvements in Air-Supply Means for Motors, of which the following is a specification.

This invention relates to air supply means for motors and the invention has for its object to provide improvements in means of the character stated whereby the air supply, and the proper proportions of air and fuel, for motors, may be readily and accurately controlled and varied in accordance with the requirements of varying working conditions.

The invention relates particularly to air supply means for internal combustion motors, such motors when used for operating vehicles requiring a wide range of proportions of fuel and air in their operation if they are to efficiently and economically supply the various demands made upon them for speed and power.

Another object is to provide means for internally cooling and scavenging the motor when a motor vehicle is traveling by virtue of its momentum and the motor is not being used for power purposes.

With the above and other objects in view, the invention consists in the novel and useful provision, formation, construction, combination, association and relative arrangement of parts, members and features, all as hereinafter described, shown in the drawing, and finally pointed out in claims.

In the drawing: Figure 1 is a fragmentary side elevation of an automobile or motor vehicle equipped with air supply means, constructed, organized and applied in accordance with the invention, parts being broken away in section for clearness of illustration; Fig. 2 is an enlarged fragmentary view partly in section taken on line x^2-x^2 , Fig. 1; Fig. 3 is a fragmentary detail view, partly in section, taken on the line x^3-x^3 , Fig. 2 and looking in the direction of the appended arrows; and Fig. 4 is a fragmentary detail view of a portion of the controlling means, taken on a line of vision from the reverse side of the showing in Fig. 1.

Corresponding parts in all the figures are designated by the same reference characters.

Referring with particularity to the drawing, A designates the body of a motor vehicle or automobile of the usual form, with wheels, axles, et cetera detached. The vehicle is provided with the usual steering post 60 B and steering wheel C and with the usual horizontal frame D upon which is mounted the motor E.

F designates the air supply means organized to embody the invention, the same being connected with the fuel supply means G of the motor E, and with controlling or operating means H, and having adjusting means J.

A particular embodiment of the invention, with respect to the specific construction and combination and inter-relation of parts, members and features, is as follows: The air supply means F comprise a tubular member 5 having a reduced terminus 6 which is threaded as at 7 into the intake pipe 8 of the motor E. The end 9 of the tubular member 5 is fitted with apertured closure 10 from which projects a boss 11. Rotatably mounted upon the boss 11 is a valve 12 provided with ports or apertures 13 arranged to be brought into registration with similar ports or apertures 14 provided in the closure 10. The valve 12 is preferably of built-up formation, the outer portion 15 being recessed as at 16 to accommodate an oscillatory shutter 17 which is held in flat facial contact with the inner face of the portion 15 by means of the disk portion 18, screws 19 serving to hold the parts in assemblage. Ports 20 are provided in the shutter 17 which may be brought into full registration with the ports 13 of the valve 12, or the shutter 17 may be so positioned by means of a finger piece or lever 21 that the ports 13 are partially or entirely closed, thus constituting the adjusting means J whereby the maximum port area and consequent maximum capacity of the valve may be fixed at any pre-determined point; the portion 15 of the valve being cut away at its periphery as at 22 to accommodate movement of the finger piece 21. The valve 12 is pressed into contact with the closure 10 by a compression spring 23 secured in place by a nut 24 on the threaded portion 25 of the boss 11. A lever 26, which is preferably integral with the outer portion of the valve, is provided for connecting the valve with operating means. Within the tubular member 5 is a slideable valve member 110

27 arranged to cover or uncover a plurality of ports 28 provided in the tubular member at such distance from its ends, that they are covered by the member 27 until it is moved to its outermost position. The central portion 29 of the valve member 27 is a puppet valve of frusto-conical formation and co-acts with a seat 30 formed interiorly of the tubular member 5 at the reduced terminus 6 thereof.

10 From the periphery of the puppet valve 29 extends lateral arms 31 carrying at their outer ends an annulus 32 which has a sliding fit in the tubular member 5 and is that portion of the valve member which covers or uncovers the aforementioned ports 28. The puppet valve 29, lateral arms 31 and annulus 32 are preferably of integral construction.

The operating or controlling means H 20 comprise a link member *h* and its co-acting parts, and a flexible member *g* with its accompaniments. The link member *h* is connected at one end with the lever 26 of the valve 12 by any suitable means as by ball 25 and socket joint 33, and connected at the other end with the mechanism which operates the throttle valve 34 of the fuel supply means G, said fuel supply means being of any preferred form as for instance a carbureter 35 such as is ordinarily employed. The mechanism for operating the throttle valve 34 may be of the usual form, such as a foot pedal or lever 36 adapted to be moved by the operator of the motor vehicle, and 30 a connecting link 37 between such lever and the throttle valve, as illustrated in Fig. 1. In usual practice such throttle operating mechanism is further connected with manually operated means 38 mounted upon the 35 steering mechanism *b* and connected with the link 37 by means of a rod 38^a, which acts against a collar 39 provided on the link 37 when the manually operated means 38 are manipulated, in this manner operating 40 the throttle valve. The specific arrangement of such throttle operating mechanism is immaterial, the only requirement being that the connections be such as will cause the operation of the valve 12 when the 45 throttle valve 34 is operated, in this particular adaptation of the invention. The flexible member *g* preferably consists of a stiff wire 40 which is secured to the valve member 27 in any suitable manner, as at 41, 50 the wire passing through a bore 42 which extends through the closure 10 and the boss 11, the wire further passing through a tightly coiled wire casing or the like 43 to a lever or finger piece 44 mounted upon a segmental support 45 fixed within easy reach of the operator of the motor vehicle. The lever 44 is pivotally secured to the support 45 as at 46 and is adapted to be thrown into three positions, being limited in throw 55 in one direction by the abutment 47 and in

the other direction by the wire 40 which is secured to the lever by means of a screw or the like 48. The lever may be held in intermediate position by frictional contact with its support or any suitable detent. One end of the coiled wire casing is secured to the support 45 by being clamped between the portions 47^a and 47^b of the lug 47, while the other end is secured to the boss 11 by means of a coupling or union 49 screwed onto the threaded portion 25 of the boss.

During the operation of the motor a gaseous fuel and air mixture is supplied to the point of combustion in the motor through the intake pipe 8, the volume of such mixture ordinarily being controlled by the throttle valve 34, while the ratio of fuel to air or richness of the mixture is largely controlled by the fixed adjustment of the carbureter or other fuel supply means. When it is considered that the motor is operated at various speeds and under widely different working conditions and must meet the ever changing requirements of the road, it will be apparent that no fixed adjustment of fuel and air proportions at the carbureter can efficiently and economically supply the proper mixture of fuel and air with which the motor can meet the various demands for power and speed. The air supply means, 85 being tapped into the intake pipe between the throttle valve and the motor, is utilized to vary the proportion of fuel to air whenever variation is required, by the dilution of the mixture formed in the carbureter, 90 which is accomplished by the addition of such proportionate amount of air as may be required to meet the aforementioned varying working conditions. When the lever or finger piece 44 is moved by the 95 operator to rest against the abutment the wire 40 is forced to move in its casing and causes the valve member 27, to which it is connected, to move inwardly in the tubular member 5, forcing the puppet valve 29 100 against its seat 30 thereby sealing the intake pipe 8 against the entrance of any air through the air supply means, in which case the motor runs on the mixture as delivered by the carbureter.

When the motor is taking in fuel mixture a partial vacuum is formed in the intake pipe which effectually keeps the puppet valve 29 to its seat and the annulus 32 in position to cover the ports 28, until unseating is caused by movement of the lever 44 by the operator of the motor car, which movement, transmitted by the wire 40, draws the puppet valve 29 from its seat, placing the intake pipe in communication with the 115 air supply means.

The valve 12 being directly connected and operable with the throttle operating means, in one manner of employing the invention, it brings the ports 13 into registration with 120

130

the ports 14 in the closure 10 or partially or wholly closes said ports 14, when the throttle is correspondingly set, the relative positions of the ports in the valve and the ports 5 in the closure being dependent on the positioning of the throttle valve. Proper harmonious working of throttle valve and valve 12 are insured by pre-determined adjustment. When the ports 13 and 14 are in such 10 positions that air may pass therethrough and the puppet valve 29 has been moved from its seat, the partial vacuum in the intake pipe 8 causes an inrush of air through the ports and tubular member into the intake pipe. During the operation just described, the annulus 32 still covers the ports 28 as the valve member 27 and the lever 44 are in their intermediate positions. When, 15 however, the lever 44 has been moved sufficiently far from the abutment 47 to cause the movement, by means of the wire, of the valve member 27 to its outermost position, the ports 28 are uncovered by the annulus 32 and air freely enters the intake pipe 25 through such ports by way of the tubular member 5, flushing the motor with air, which scavenges and cools the interior of the motor, and relieves any partial vacuum in the intake pipe, thereby reducing the 30 draft on the carburetor to a minimum or to zero. This position of the valve member may be used to advantage in coasting down hills when the motor is not needed for power. The provision of the adjusting 35 means J for varying the effective port area of the valve 12 adapts the invention to a wide range of motor requirements. The lever 26 of the valve 12 may, it is manifest, be arranged to be operated independently of 40 the throttle valve if desired.

Having thus described my invention, I claim and desire to secure by Letters Patent:

1. The combination, with a motor having a fuel intake pipe; of air supply means communicating with the fuel intake pipe, a throttle valve for the fuel intake pipe, and operative connections between said air supply means and said throttle valve; said air supply means comprising valve means for regulating the supply of air to said intake pipe in proportion to the fuel mixture permitted to pass the throttle valve to the motor, and other valve means normally closed and adapted to be opened to admit

air to said intake pipe independently of said first named valve means.

2. The combination, with a motor having a fuel intake pipe; of air supply means communicating with the fuel intake pipe, a throttle valve for the fuel intake pipe, and operative connections between said air supply means and said throttle valve; said air supply means comprising valve means for regulating the supply of air to said intake pipe in proportion to the fuel mixture permitted to pass the throttle valve to the motor, and other valve means normally closed and adapted to be opened to admit air to said intake pipe independently of said first named valve means; and independent means 65 for operating said last named valve means.

3. The combination, with a motor having a fuel intake pipe and a throttle valve for the fuel intake pipe; of a tubular member communicating with said fuel intake pipe 75 and having a lateral air port, a valve slideable in said tubular member and seating to terminate communication between said intake pipe and said tubular member, said valve also normally closing said lateral air inlet port, a rotatable valve at the other end of said tubular member and controlling the admission of air thereto, and operative connections between said rotatable valve and said throttle valve.

4. The combination, with a motor having a fuel intake pipe; of air supply means communicating with the fuel intake pipe, a throttle valve for the fuel intake pipe, and operative connections between said air supply means and said throttle valve; said air supply means comprising valve means for regulating the supply of air to said intake pipe in proportion to the fuel mixture permitted to pass the throttle valve to the motor, and other valve means normally closed and adapted to be opened to admit air to said intake pipe independently of said first named valve means and further adapted to entirely cut off said air supply means from 100 said fuel intake pipe.

In testimony whereof, I have signed my name to this specification in the presence of two subscribing witnesses.

WILLIAM A. WATKINS.
